ABSTRACT OF THE DISCLOSURE

A machine for dispensing stock along a discharge path from a coil thereof and comprising a frame and a turntable mounted thereon. The machine further includes an accumulating device having a platform carried on the frame and disposed at a preselected location in the discharge path downstream of a coil of stock for receiving and accumulating one or more coils of stock and providing a high pay-out rate at the beginning of the dispensing cycle.

This invention relates to coil stock handling equipment and particularly concerns dispensing machines for paying-out strap and similar coil stock.

A principal object of the invention is to provide an improved dispensing machine for intermittently paying-out stock at a high speed without danger of its being overstressed, buckling or otherwise over-running during the course of a dispensing cycle.

Another object of the invention is to provide an improved dispensing machine particularly suited to quickly and smoothly dispense stock at a high pay-out rate in response to a sudden demand.

A further object of the invention is to provide an improved dispensing machine having power means for rotating a coil of stock which additionally provides a braking action for quickly stopping its rotation to maintain continuous, uninterrupted control of the stock.

A still further object of the invention is to provide an improved dispensing machine which readily handles heavy coiled stock and which provides reliable operation over a long service life.

Other objects will be in part obvious and in part pointed out more in detail hereinafter.

The invention accordingly consists in the features of construction, combination of elements and arrangement of parts which will be exemplified in the construction hereafter set forth and the scope of the application which will be indicated in the appended claims.

In the drawings:

FIG. 1 is a side elevational view, partly in section and partly broken away, showing a preferred embodiment of a dispensing machine constructed in accordance with the invention, and a sectional view of a coil of strap illustrated in broken lines as being loaded on the dispensing machine to be paid-off therefrom;

FIG. 2 is an enlarged fragmentary view taken generally along line 2—2 of FIG. 1;

FIG. 3 is a top plan view showing the dispensing machine in full lines as being partly broke away and the coil of stock in broken lines;

FIG. 4 is an enlarged view, partly broken away and partly in section, taken generally along line 4—4 of FIG. 3; and

FIG. 5 is a schematic diagram of an electrical control system incorporated in the invention.

Briefly stated, the invention is embodied in a dispensing machine, described more specifically below, having a frame for supporting a turntable assembly upon which a coil of stock, such as strap, e.g., is loaded to be dis-

2

pensed from the machine. To ensure that stock will be available to be intermittently dispensed at a high payout rate, an accumulating device is secured to the frame above the turntable assembly for receiving and accumulating a predetermined length of coiled stock from the coil on the turntable assembly. The free end of stock is then fed from the accumulating device through a discharge station to associated stock handling equipment desirably provided with power means for withdrawing stock but which forms no part of this invention. When stock is suddenly withdrawn from the dispensing machine through the discharge station, additional stock is automatically fed into the accumulating device and the turntable is power driven in a coil unwinding direction to assist in paying out stock and, after a desired length of stock has been payed out, to quickly resupply the accumulating device with a sufficient quantity of expanded coiled stock for the next high speed dispensing operation.

Referring now to FIGS. 1 and 3 of the drawings wherein a preferred embodiment of the invention is illustrated, a rigid frame 10 is shown which includes a horizontal support beam 11 desirably fabricated of U-shaped channel bar having one end supported by a vertical leg 12 and an opposite end secured at the midpoint of a cross member 14. The latter has a leg 16 at each of its opposite ends with a caster 18 mounted at the foot of each leg 16 to render the frame 10 movable. To facilitate maneuvering the frame 10, a handle 20 is fixed to leg 12 and support beam 11 at its end opposite the cross member 14.

Below the support beam 11 is a reel or turntable assembly upon which a coil 22 of strap is illustrated as being loaded on a generally circular turntable 24. The turntable 24 has an internally threaded sleeve 25 rigidly fixed at its center to extend axially upward thereof when the turntable 24 is in its illustrated horizontal position, and reinforcing braces 26 are shown secured to the bottom surface of the turntable 24 to provide rigidity. A segment of the turntable 24 is preferably removed to form a straight edge 27 (FIG. 3), and a pair of feet 28 are fixed to the turntable 24 in an upright position at opposite ends of edge 27 whereby, upon being disassembled from the frame 10, the entire turntable assembly may be tipped upward into a vertical position on a supporting floor, not shown, to rest on the feet 28. This may be accomplished, e.g., by a crane having a hook, not shown, secured in the eye 29 of a heavy-duty lug 30 secured on the turntable 24 in diametrically opposed relation to its edge 27. A heavy coil of strap, typically in the order of 1000 pounds, may then be readily positioned on the turntable 24 whereupon both the coil 22 and turntable 24 may be eased back into a horizontal position on the floor.

To couple the frame 10 to the turntable 24 an elongated screw assembly 31, shown in broken lines in FIG. 1, is extended through a hollow shaft 32 which is journaled in a housing 33 for rotation about a vertical axis, the housing 33 being fixed to the frame 10 in a vertical position intermediate the ends of the support beam 11. The screw assembly 31 includes a threaded lower end 34 which is coaxially received within the upright sleeve 25 of the turntable 24 for rotatably supporting the same in a horizontal position. The hollow shaft 32 and turntable 24 are thus adapted to be coupled and, preferably, keyed together against relative movement, and a manually operable crank 35 is secured on the upper end 36 of the screw assembly 31 whereby even a fully loaded turntable assembly may be readily cranked-up by hand off the floor into an operative position below the support beam 11.

The hollow shaft 32 is power operated by a unidirec-

tional electric motor 38 mounted to one side of the support beam 11 adjacent the cross member 14. The motor 38 is operatively connected to an output or drive shaft 39 having a drive sheave 40. To rotate the turntable 24 in a coil unwinding direction, motor 38 is drivingly connected to the hollow shaft 32 by an endless V-belt 42 horizontally supported by the drive sheave 40 and by a driven sheave 44 secured to the upper end of the hollow shaft 32 just below the crank 35.

To provide a machine which is capable of suddenly and smoothly dispensing strap at a high initial pay-out rate even when the turntable 24 is stationary, an accumulator 50 is provided in accordance with this invention for holding a predetermined number of expanded coils of strap available to be suddenly payed out from the machine.

The accumulator 50 essentially consists of a shallow storage tray having a circular outer rim or ring 52 rigidly fixed to the support beam 11. In the specific illustrated embodiment, a series of upper braces 54 extend horizontally inwardly from points of attachment at the top edge of the outer ring 52 and are shown secured to the bottom of the support beam 11 which is illustrated as extending diametrically of the outer ring 52. To support coils of strap within the accumulator 50, a series 20 of lower braces 56 are rigidly fixed to the bottom edge of the outer ring 52 and constituting a platform extending inwardly thereof in a horizontal plane.

An inner ring 58 is secured inside the outer ring 52 of the accumulator 50 between the upper and lower braces 54 and 56 in symmetrical relation to the overlying support beam 11 whereby an annular compartment is formed between the inner and outer rings 58, 52 for receiving coiled strap. The inner ring 58 is offset from the center of the outer ring 52 toward the cross member 14 and is shown as being mounted in eccentric relation to the hollow shaft 32. A hollow stationary drum 60 having a diameter somewhat less than that of the inner ring 58 is fixed to the lower brace structure and depends below the inner ring 58 in concentric relation to the hollow shaft 32. Thus, when the turntable 24 is coupled to the frame 10, the stationary drum 60 and the turntable 24 cooperate to provide a strap dispensing reel wherein the drum 60 is coaxially aligned with the turntable 24 and spaced inwardly of the coil 22.

A portion of the outer ring 52 is split, adjacent the juncture of the support beam 11 and cross member 14, to provide a discharge opening at 62, and an adjacent portion of the inner ring 58 is removed to form a gap at 63. A flexible discharge guide 64, preferably formed by a closed coil spring positioned at the discharge opening 62, is shown secured to and extended tangentially of the outer ring 52 in parallel relation to the cross member 14. The discharge guide 64 is mounted on a support 66 which in turn is secured to a brace 68 extending parallel to the support beam 11, the brace 68 being rigidly fixed to the inner and outer rings 58, 52 thereby serving also to reinforce the accumulator 50.

So that strap from the inner periphery of coil 22 may be fed upward and radially outward of the drum 60 through the gap 63 in the inner ring 58 and into the accumulator 50, a feed wheel 70 is mounted adjacent the discharge guide 64 on the lower end of a vertical shaft 72 which is journaled in a housing 74 (FIG. 1) fixed to the side of the support beam 11 opposite the motor 38 which drives the turntable 24. The motor 38 also serves to drive the feed wheel 70. A drive pulley 76 is mounted on the drive shaft 39 in spaced coaxial relation below the drive sheave 40 to provide a clearance between the drive pulley 76 and drive sheave 40, and an 60 endless V-belt 78 is horizontally supported by the drive pulley 76 and by a driven pulley 80. The driven pulley 80 is mounted in coaxial alignment with the feed wheel 70 on the upper end of the vertical shaft 72 whereby the feed wheel 70 is drivingly connected to the motor 38. 75

Suitable strap guides, not shown, may be provided to ensure that the strap is properly fed upwardly from the coil 22 past the feed wheel 70 and into the annular compartment of the accumulator 50.

To continuously control feeding of the strap into the accumulator 50, a pressure roller 82 is provided to coat with the feed wheel 70 so as to positively grip the strap. The pressure roller 82 is suspended for rotation from a free end of a pivot arm 84 mounted on the support beam 11 adjacent feed wheel 70 for swinging movement in a horizontal plane. The pivot arm 84 is provided with a nut adjustment 86 for selectively positioning the pressure roller 82 relative to the feed wheel 70 and thereby to provide a predetermined pressure on strap fed between the feed wheel 70 and the pressure roller 82 in accordance with the thickness of the strap loaded on the turntable 24.

It has been found that improved strap dispensing is obtained by controlling the operation of the turntable 24 independently of the feed wheel 70, both of which, as described above, are preferably driven by the motor 38. For this purpose, a releasable clutch mechanism is shown in FIGS. 1 and 4 for selectively engaging the driving connection between the motor 38 and the turntable 24, the clutch mechanism including in part a drive sheave 40. The drive sheave 40 is split into separable upper and lower sheave parts 92 and 94 respectively engaging the upper and lower edges of the V-belt 42. The upper sheave part 92 is secured to the drive shaft 39, e.g., by a pin 96. The lower sheave part 94 is supported for rotation on the drive shaft 39 by means of a commercially available ball bearing assembly 100. The latter is retained in an annular compartment formed between the upper and lower sheave parts 92, 94 and includes an inner race 102 fixed to the drive shaft 39 and an outer race 104 engaging the lower sheave part 94, the inner and outer races 102, 104 providing a raceway for bearing balls such as that shown at 105.

To operate the above-described clutch mechanism, a pair of generally horizontal rocker arms 106 are positioned in the previously described clearance between the drive sheave 40 and the drive pulley 76 and are pinned at their midpoints to opposite sides of a floating collar 107. The floating collar 107 is mounted for axial movement on the drive shaft 39 and engages the bottom of the lower sheave part 94. The rocker arms 106 overlie the support beam 11 and are interconnected at one of their ends by a pivot pin 108 fixed to a brace member 110 secured to the cross member 14. The opposite ends of the rocker arms 106 are joined by a pivot pin 112 which is fixed to a vertical actuating rod 114 operatively connected to a clutch solenoid 116 mounted on the support beam 11.

Upon energizing the clutch solenoid 116, the actuating rod 114 is fully extended to force the rocker arms 106 and the floating collar 107 upward to wedge the V-belt 42 between the drive sheave parts 92, 94 and thereby rotate the turntable 24 under the power of the motor 38. Alternately, upon de-energizing the clutch solenoid 116, the actuating rod 114 is retracted to pull down the rocker arms 106 whereby the floating collar 107 and the lower sheave part 94 drop down to declutch the V-belt 42 and render the driving connection between the motor 38 and turntable 24 inoperative, even though the motor 38 remains energized.

During a dispensing operation, control of the strap is assisted by a turntable damping device (FIGS. 2 and 3) having a brake shoe 118 with brake pad 120 bonded to its bottom surface for frictionally engaging the turntable 24. The brake shoe 118 is mounted inside the stationary drum 60 by a pivot pin 122, and a free end of the brake shoe 118 is pinned to a vertical rod 124 operatively connected to a brake solenoid 126 secured within the drum 60 above the brake shoe 118. Upon being energized, the brake solenoid 126 actuates the rod 124

into a fully extended position causing the brake pad 120 to engage the turntable 24 to prevent its free turning. The brake shoe 118 and pad 120 are thereafter lifted away from the turntable 24 when the rod 124 is retracted upon de-energization of the brake solenoid 126. The braking action is aided by a coil spring 128 suitably retained on the rod 124 to continuously urge the brake shoe 118 into frictional engagement with the turntable 24.

The operation of the motor 38, the clutch solenoid 116 and the brake solenoid 126 is controlled by an electrical control system having a manually operated master switch 132 mounted upon the support beam 11 and connected to a suitable source of electrical power, not shown. The operation of the motor 38 is governed by a suitable cycle control switch 134 adjacent the master switch 132 on the support beam 11. The cycle control switch 134 includes a pivotally mounted actuator or sensing arm 138 biased by suitable means radially inward through an opening in the outer ring 52 of the accumulator 50 for maintaining the cycle control switch 134 in a closed position energizing the motor 38 in the absence of relaxed, expanded coils of strap in the accumulator 50.

To operate the clutch solenoid 116, a normally open turntable control switch 139 is provided which additionally governs the operation of the brake solenoid 126. The turntable control switch 139 is mounted inside the stationary drum 60 on a bracket 140 depending from the lower brace structure 56 and is actuated by an attached arm 142 similar in function to the sensing arm 138 of the cycle control switch 134. One end of the arm 142 is operatively connected to the turntable control switch 139 and its opposite end extends outward through an opening in the drum 60 to engage a shoe 144 pivotally mounted for radial movement on the outer surface of the drum 60. The shoe 144 is biased radially outward of the drum 60 to maintain the turntable control switch 139 in its normally open condition. Contraction of the strap about the drum 60 will cause the shoe 144 and the arm 142 to move radially inward to close the turntable control switch 139, and upon expansion of the strap away from the drum 60, the shoe 144 and the arm 142 move radially outward to return the turntable control switch 139 to its normally open condition.

It is believed that the operation of the invention will be apparent in view of the above description together with the following explanation of its operation.

After the turntable assembly is loaded and coupled to the frame in operative position below the support beam 11, a length of strap is unwound from the inner periphery of the coil 22 and threaded between the feed wheel 70 and the pressure roller 82, through the gap 63 and into the accumulator 50 between its inner and outer rings 58 and 52. After a desired length of coiled strap, typically about six wraps or a total of approximately 40 feet, has been pulled into the accumulator 50, the free end of the strap is fed through the opening 62 out through the discharge guide 64. A curved discharge path for strap is thus provided which extends from the coil 22 downstream through the accumulator 50 and out through the discharge guide 64 so that the free end of the strap may be withdrawn from the accumulator 50 such as by auxiliary power operated strap handling equipment, not shown.

The strap loaded on the turntable 24 at the upstream end of the discharge path is fanned inward from the coil 22 and, as best seen in FIG. 1, is normally spaced radially outward of the stationary drum 60. Downstream of the feed wheel 70, the coiled strap in the accumulator 50 is relaxed with the outermost coil expanded to a diameter greater than that of the coil 22 and bulged outward against the outer ring 52, forcing the sensing arm 138 radially outward and thereby opening the normally closed cycle control switch 134 and maintaining the motor 38 in a de-energized state.

Upon turning the master switch 132 ON, both the

clutch solenoid 116 and the brake solenoid 126 are initially energized whereby the drive sheave 40 is in clutching engagement with the V-belt 42 and the brake pad 120 is engaged with the turntable 24. Thereafter, the strap may be rapidly pulled through the discharge guide 64 at a high pay-out rate in the order of 6 feet per second, and the dispensing of strap is immediately sensed by the sensing arm 138 which pivots radially inward responsive to the contraction of strap within the accumulator 50. The cycle control switch 134 is immediately closed to energize the motor 38 and activate the feed wheel 70 to automatically begin pulling strap from the coil 22 into the accumulator 50. The clutch solenoid 116, which as indicated above is operated by the turntable control switch 139, is also electrically connected to the cycle control switch 134 and is de-energized at the same time the cycle control switch is closed to initially energize the motor 38. The V-belt 42 thus is disengaged to uncouple the motor 38 and the turntable 24 at the beginning of the dispensing cycle.

As the feed wheel 70 is feeding strap into the accumulator 50 in response to strap withdrawal through the discharge guide 64, the strap on the turntable 24 rapidly contracts radially inward from the coil 22 to collapse about the stationary drum 60, moving the shoe 144 and its associated arm 142 radially inward to close the normally open turntable control switch 139. This de-energizes the brake solenoid 126 to release the turntable 24 for rotation and simultaneously re-energizes the clutch solenoid 116 whereby the turntable 24 is accelerated in a coil unwinding direction under the power of the motor 38 to assist paying out strap.

When the demand for strap ceases and strap is no longer being withdrawn through the discharge guide 64, the strap coiled about the stationary drum 60 expands radially outward to release the shoe 144 and reopen the turntable control switch 139. The clutch solenoid 116 is then again de-energized to uncouple the driving connection to the turntable 24, and the brake solenoid 126 once again is energized whereby the brake pad 120 re-engages the turntable 24 to dampen its rotation. The feed wheel 70 continues to operate under the power of the motor 38 to feed strap into the accumulator 50 which now fans out to its fully expanded condition and engages the sensing arm 138 to reopen the cycle control switch 134 and de-energize the motor 38, thereby to simultaneously deactivate the feed wheel 70 and to re-energize the clutch solenoid 116.

It will now be seen that the turntable 24 is again coupled to the motor 38 which, in its de-energized condition, effectively provides an additional braking action assisting the brake pad 120 to quickly stop the rotation of the turntable 24 despite its heavy mass and thereby ensure against any tendency of the strap to buckle, become kinked or otherwise over-run.

The machine is now at rest and, upon turning the master switch 132 OFF, both the clutch and the brake solenoids 116 and 126 are de-energized. The accumulator 50 is again fully supplied with coiled strap such that the machine is conditioned for a repeat dispensing operation.

The present invention thus provides for smoothly dispensing stock at a high pay-out rate in response to a sudden demand. Once the machine is activated, the dispensing operation is entirely automatic and shock-free with minimal time delay between the time the stock is initially withdrawn from the accumulator 50 until the turntable 24 is braked to a stop with the accumulator 50 fully resupplied with coiled stock in readiness for the next dispensing cycle. The smooth automatic nature of the operation assures continuous uninterrupted control of the stock to effectively prevent its over-running or being overstressed despite the high speed of the dispensing operation and the heavy weight of the coiled stock.

As will be apparent to persons skilled in the art, various modifications and adaptations of the structure above-de-

scribed will become readily apparent without departure from the spirit and scope of the invention, the scope of which is defined in the appended claims.

We claim:

1. A coil handling machine for dispensing stock along a discharge path from a coil thereof comprising a frame, a reel mounted on the frame for supporting a coil of stock for rotation, and an accumulating device including a platform carried on the frame at a preselected location in the discharge path downstream of a coil of stock for receiving and accumulating one or more coils of stock so that the same may be suddenly withdrawn from the accumulating device at a high pay-out rate at the beginning of a dispensing cycle.

2. The machine of claim 1 including a driven feed wheel supported for rotation on the frame, the feed wheel being positioned in the discharge path upstream from the accumulating device for pulling stock from a coil thereof and feeding it along the discharge path into the accumulating device, and operating means mounted on the frame for operating the feed wheel in response to the withdrawal of stock from the accumulating device.

3. The machine of claim 1 including driving means mounted on the frame for rotating the reel in a coil unwinding direction during the withdrawal of stock from the accumulating device.

4. A coil handling machine for dispensing stock along a discharge path from a coil thereof comprising a frame, a vertical shaft rotatably supported on the frame and having a lower end depending below the frame, a turntable for supporting a coil of stock for rotation, the turntable being removably secured in a horizontal position to the lower end of the vertical shaft whereby the turntable may be removed bodily from the frame to facilitate loading a coil of stock in the machine, and a stationary accumulating device fixed to the frame at a preselected location in the discharge path downstream of a coil of stock for receiving and accumulating a predetermined length of coiled stock so that the same may be suddenly withdrawn from the accumulating device at a high pay-out rate at the beginning of a dispensing cycle.

5. A coil handling machine for dispensing stock along a discharge path from a coil thereof comprising a frame and a stationary accumulating device fixed to the frame at a preselected location in the discharge path downstream of a coil of stock for receiving and accumulating a predetermined length of coiled stock so that the same may be suddenly withdrawn from the accumulating device at a high pay-out rate at the beginning of a dispensing cycle, the accumulating device comprising a traylike container of generally circular shape including an outer ring, and an inner ring secured inside the outer ring and defining an annular compartment therebetween for receiving and accumulating a plurality of expanded coils of stock, the outer ring having a discharge opening therein communicating with the annular compartment formed between the inner and outer rings.

6. The machine of claim 2 further including a pressure roller rotatably supported on the frame and cooperating with the feed wheel to positively engage stock for pulling the same from a coil thereof, and means for adjusting the pressure roller relative to the feed wheel.

7. The machine of claim 2 wherein the operating means include a motor mounted on the frame, a driving connection between the motor and the feed wheel, and a switch operatively connected to the motor and having a switch actuator engageable with coiled stock in the accumulating device, the switch actuator being responsive to contraction and expansion of coiled stock in the accumulating device for sensing the withdrawal of stock, thereupon to operate the motor and the feed wheel, and for de-energizing the same at the end of a dispensing cycle when the accumulating device is fully resupplied with stock.

8. The machine of claim 2 including a motor drivingly

connected to the feed wheel, a driving connection between the motor and the reel, and control means for selectively engaging the driving connection between the motor and the reel to alternately couple and uncouple the same as determined by the tensioning of stock pulled from a coil thereof by the feed wheel.

9. A coil handling machine for dispensing stock along a discharge path from a coil thereof comprising a frame, a stationary accumulating device fixed to the frame at a preselected location in the discharge path downstream of a coil of stock for receiving and accumulating a predetermined length of coiled stock so that the same may be suddenly withdrawn from the accumulating device at a high pay-out rate at the beginning of a dispensing cycle, the accumulating device including a circular rim having a discharge opening therein through which stock is payed out, the circular rim being engageable with stock contained in the accumulating device in a fully expanded relaxed condition, a driven feed wheel supported for rotation on the frame, the feed wheel being positioned in the discharge path upstream from the accumulating device for pulling stock from a coil thereof and feeding it along the discharge path into the accumulating device, a motor mounted on the frame, a driving connection between the motor and the feed wheel, and a switch operatively connected to the motor and having a switch actuator engageable with coiled stock in the accumulating device, the switch actuator being located on the circular rim for operating the motor and the feed wheel responsive to the withdrawal of stock from the accumulating device as determined by contraction of stock radially inward of its circular rim, the switch actuator additionally being responsive to expansion of coiled stock in the accumulating device for de-energizing the motor and the feed wheel at the end of a dispensing cycle when the accumulating device is fully resupplied with stock.

10. A coil handling machine for dispensing stock along a discharge path from a coil thereof comprising a frame, a stationary accumulating device fixed to the frame at a preselected location in the discharge path downstream of a coil of stock for receiving and accumulating a predetermined length of coiled stock so that the same may be suddenly withdrawn from the accumulating device at a high pay-out rate at the beginning of a dispensing cycle, a driven feed wheel supported for rotation on the frame, the feed wheel being positioned in the discharge path upstream from the accumulating device for pulling stock from a coil thereof and feeding it along the discharge path into the accumulating device, a motor mounted on the frame, a driving connection between the motor and the feed wheel, a switch operatively connected to the motor and having a switch actuator engageable with coiled stock in the accumulating device, the switch actuator being responsive to contraction and expansion of coiled stock in the accumulating device for sensing the withdrawal of stock, thereupon to operate the motor and the feed wheel, and for de-energizing the motor and the feed wheel at the end of a dispensing cycle when the the accumulating device is fully resupplied with stock, a reel mounted on the frame for supporting a coil of stock for rotation, a driving connection between the motor and the reel for rotating the reel in a coil unwinding direction during the withdrawal of stock from the accumulating device, and a disengagable clutch in the driving connection between the motor and the reel for selectively coupling the same, the switch being operatively connected to the clutch for engaging the same when the motor is de-energized at the end of a dispensing cycle thereby to effect an automatic braking action on the reel to quickly stop its rotation when the accumulating device is fully resupplied with stock.

11. A coil handling machine for dispensing stock from a coil thereof comprising a frame, a turntable mounted on the frame for supporting a coil of stock for rotation, a stationary drum secured to the frame centrally of the turntable in concentric relation to its rotational axis, a

stationary accumulating device fixed to the frame for holding a plurality of expanded coils of stock so that the same may be contracted and suddenly withdrawn at a high payout rate at the beginning of a dispensing cycle, a feed wheel mounted on the frame for feeding stock from the turntable into the accumulating device to re-supply stock dispensed therefrom, and power operated driving means for controlling the rotation of the turntable and the feed wheel.

12. The machine of claim 11 wherein the accumulating device includes a circular rim axially displaced from the turntable in eccentric relation to its rotational axis.

13. The machine of claim 11 wherein the power operated driving means include a motor, a first driving connection between the motor and the feed wheel, and a second driving connection between the motor and the turntable including a clutch mechanism for selectively coupling the motor and the turntable and controlling the operation thereof independently of the feed wheel.

14. The machine of claim 13 including switching means operatively connected to the motor and to the clutch mechanism, the switching means including a switch actuator located on the accumulating device and engageable with stock therein when the same is in a fully expanded relaxed condition, the switching means being operated by the switch actuator to energize the motor and deactivate the clutch mechanism in response to the contraction of stock in the accumulating device, and to de-energize the motor and activate the clutch mechanism in response to the expansion of stock in the accumulating device into engagement with the switch actuator, whereby the de-energized motor effects an automatic braking action on the turntable at the end of a dispensing cycle.

15. The machine of claim 13 including switching means operatively connected to the clutch mechanism and including a switch actuator located on the stationary drum, the switching means being operated by the switch actuator to cause the clutch mechanism to couple the motor and

the turntable in response to stock pulled by the feed wheel into engagement with the switch actuator thereby to rotate the turntable under the power of the motor until the switch actuator is disengaged by the expansion of stock radially outward of the drum.

5 16. The machine of claim 13 including an output shaft connected to the motor, a drive sheave mounted on the output shaft having a first sheave part fixed thereto and a second sheave part, the latter being supported for rotation on the output shaft and axially movable relative to the first sheave part, a driven sheave drivingly connected to the turntable, an endless driving belt externally mounted on the drive sheave and the driven sheave, a floating collar mounted for axial movement on the output shaft and engaging the second sheave part of the drive sheave, and an actuator operatively connected to the floating collar for moving the same between an extended position frictionally clutching the belt between the sheave parts of the drive sheave, and a retracted position releasing the belt from clutching engagement thereby to provide the clutch mechanism for selectively coupling the motor and the turntable.

10 17. The machine of claim 15 further including damping means mounted on the drum and selectively engageable with the turntable, the damping means being actuated by the switching means for engaging the turntable and retarding its rotation when the clutch mechanism coupling the motor and the turntable is disengaged.
